PRESSURE OPERATED FOLLOW-UP SYSTEM

William A. Ray, North Hollywood, Calif., assignor
to General Controls Co., Glendale, Calif., a cor-
poration of California

Application August 23, 1947, Serial No. 770,265

7 Claims. (Cl. 121—41)

1

This invention relates to control systems and more particularly to systems for controlling burners of the fluid-fuel consuming type. The invention, in one of its aspects, relates more particularly to a fluid-pressure-operated control system which includes a pilot-valve-controlled pressure operator having follow-up means for positioning the operator at a point or points intermediate its limits of movement. The present invention is, in some respects, an improvement upon the inventions disclosed in my Patents No. 2,317,640 and No. 2,331,502 issued, respectively, April 27, 1943 and October 12, 1943.

In heating installations which include a furnace having a fluid-fuel consuming burner, it has been observed that upon initiation of operation of the furnace severe reverberations frequently occur, especially in large installations, which reverberations may cause damage to the furnace and so affect the setting of associated control apparatus that readjustment is necessary. I have found that this trouble is mainly due to the fact that, if the flue or stack of the furnace is cold when the fire is started, there may be insufficient or no draft, or even "negative" draft.

It is therefore an object of this invention to avoid such trouble, and I accomplish this object by providing a system which includes a fuel-supply valve having means normally so restricting its opening that full flow of fuel to the burner is prevented, and means responsive to the existence of proper draft in the flue or stack, after a low-fire condition has been established, for so conditioning the valve that it then can open to full capacity.

Another object of the invention is to provide a fluid-pressure operated control system which, while particularly adapted for accomplishment of the preceding object, is capable of performing various other controlling functions.

For full understanding of the invention, and further appreciation of its objects and advantages, reference is to be had to the following detailed description and accompanying drawing, 45 and to the appended claims.

In the drawing:

Figure 1 is a schematic view of a gas-burner control system embodying the invention;

Figure 2 is an enlarged view, mainly in section, of the valve structure shown in Fig. 1;

Figure 3 is an enlarged sectional view of the governor unit of the valve structure of Fig. 2;

Figure 3a is a detail section taken along the line 3a—3a of Figure 3;

2

Figure 4 is a fragmentary sectional view of a simplified form of the governor unit shown in Figs. 3 and 3a; and

Figure 5 is a sectional view showing essential parts of the governor-unit pilot-valve in positions assumed in operation.

Referring first briefly to Fig. 1 of the drawing, the numeral 11 indicates a boiler furnace having a gas burner 12 whose fuel supply is controlled by a valve structure generally indicated at 13 and shown in detail in the other figures of the drawing. The other apparatus in Fig. 1 will be described hereinafter with reference to the operation of the system.

15 In Fig. 2, the numeral 14 indicates a main valve casing having an inlet 15 and an outlet 16 separated by a partition 17. Threaded in an opening through the horizontal portion of the partition is an annular seat member 18 with 20 which a main closure 19 cooperates; the closure being provided with guide vanes 20 fitting the bore of the seat member. For operating the closure 19 manually, under abnormal circumstances, there is a screw 21 engageable with the closure and threaded in an opening in the bottom of the casing normally covered by a cap 22.

25 Mounted above the top of the valve casing 14, by means of a hollow spacing-member 23, is a diaphragm motor comprising opposed dished plates 24 and 25 which are joined together at their flanges with the marginal portion of a flexible diaphragm 26 therebetween to form an upper and a lower pressure-chamber 27 and 28, respectively. The lower dished plate 25 is centrally apertured so that the chamber 28 is in communication with the interior of the spacing member 23. On opposite sides of the movable-wall or diaphragm 26 is a pair of stiffening plates 29 to which a rod 30 is secured; the rod being connected at its lower end to the closure 19 and guided in a central opening through the bottom wall 31 of the spacing member. In the wall 31 is another opening 32 which affords continuous communication between the valve-casing inlet 15 and the lower diaphragm-chamber 28.

30 Resting on top of the diaphragm plates 29, and guided in a sleeve 33 mounted in an opening through the upper dished plate 24, is a rod 34 which is pivotally connected at its outer end to a damper arm 35 pivoted at its left-hand end on the diaphragm motor. Leakage around the rod 34 is prevented by a bellows 36 encompassing the inner end of the rod. Since the rod 34 is not attached to the diaphragm plates, seating of the 35 main closure 19 would not be impeded in the

event that the damper arm 35 were accidentally held in raised position.

For controlling the operation of the diaphragm motor there is, mounted on the top of the same, a three-way pilot valve generally indicated at 37. This pilot valve comprises a casing having a central chamber 39 whose top and bottom walls are ported to provide valve seats with which a closure 40 alternately cooperates; the closure being connected by its stem to an electric solenoid 41. When the solenoid is energized and the closure 40 resting by gravity on the lower seat, as shown, the upper chamber 27 of the diaphragm motor is in communication with the inlet 15 of the valve casing by way of a passage 42 (interconnecting the diaphragm chamber 27 and the pilot-valve chamber 39), the open upper pilot-valve port, and a pipe 43 which connects the space 44 above the upper pilot-valve port to the interior of the spacing member 23 and thereby to the main inlet 15.

Assuming that the valve inlet 15 is connected to a source of gaseous fuel, the pressure of the fuel is applied equally to both sides of the movable-wall or diaphragm 26 when the pilot valve 37 is in the condition shown and described; the diaphragm therefore being in its depressed position under the force of gravity acting on its associated parts, and the main closure 19 seated.

When the solenoid 41 is energized, the pilot-valve closure 40 is raised to close the upper port (so that communication between the diaphragm chamber 27 and the supply of pressure fluid is obstructed) and to open the lower port so that the space 45 below it then communicates with the diaphragm chamber 27. This space 45 is connected by a pipe 46 to the valve structure 47 of a governor unit 48, both hereinafter to be described. The valve structure 47 has a vent pipe 49 with which, under certain conditions of the valve structure, the pipe 46 is in communication, so that under those conditions the fluid compressed in the diaphragm chamber 27 can vent to atmosphere when the pilot-valve closure 40 is raised, whereupon the pressure in chamber 28 below the diaphragm becomes effective to raise the diaphragm and the main closure 19 to their full extent. In practice, the vent pipe 49 is extended adjacent the burner 12 shown in Fig. 1.

The governor unit 48 is mounted on the spacing member 23 and, as can be seen in Fig. 3, comprises an elongated casing 60 bored at both ends and having an intermediate partition 61.

Extending from the left-hand end of the casing 60 is the valve structure 47 which comprises a hollow member 62 sealingly secured in the casing bore and having at its top a threaded opening 49' for the vent pipe 49 shown in Fig. 2. Threaded in the inner or right-hand end of the member 62 is a brushing 63 wherein a tubular member 64 is slidable. This member has on its left-hand end a conical head or closure 65 which cooperates with a valve seat 66 formed by the inner end of a fitting 67 threaded in the outer end of the member 62; to which fitting the pipe 46, shown in Fig. 2, is connected. Leakage of fluid around the member 64 is prevented by a flexible bellows 68 sealed to the head 65 and the bushing 63. The tubular member 64 is urged in a left-hand direction by a relatively light spring 69 compressed between the bushing 63 and a washer secured to the head or closure 65. Within the member 64 is a rod 70 which carries a spherical closure 71 cooperable with the adjacent left-hand end of the member, this closure being urged to

seated position by a spring 72 (whose force is considerably greater than that of spring 69) compressed between the right-hand end of bushing 63 and a collar 73 adjustably secured to the rod 70.

Threaded in an opening in the governor-unit partition 61, and extending to the right thereof, is an elongated member 74 whose right-hand portion is bored concentrically to freely receive the stem 75 of a pressure motor generally indicated at 76. This motor comprises a cup-shaped housing 77 secured to the casing 60 and containing an expansible-contractible metallic bellows 78 which is sealingly secured at its opposite ends to the housing 77 and to a plate or head 79 to which the motor stem 75 is connected. In the side wall of housing 77 is a fitting 80 whereby the space or chamber between the housing and the bellows can be subjected to the pressure of a controlling fluid, which fluid may be the steam generated in the boiler 11 shown in Fig. 1, as indicated by the pipe 81 extending between the fitting 80 and the upper region of the boiler. Opposing the fluid pressure in the motor is a spring 82 compressed between the bellows head and a nut 83 threaded on the member 74; a ball-bearing thrust washer 84 being provided to facilitate adjustment of the nut.

The left-hand portion of member 74 is bored concentrically to receive a rod 85; the member having a recess in its left-hand face for packing 86, held in place by a snap-ring and washer, whereby leakage around the rod is prevented. Cut horizontally through the member 74 is an elongated slot 87 (better seen in Fig. 4) for a cross-bar 88 through the medium of which the motor-stem 75 can drive the rod 85; a stop-nut 89, adjustably threaded on the member 74, limiting left-hand movement of the cross-bar and thereby the movement in that direction of the stem 75 and rod 85.

As shown in Fig. 3, the left-hand extremity of the stem 75 is spaced from the cross-bar 88; the cross-bar being held in engagement with the stop-nut 89 by a lever 90 having an annular intermediate portion (see Fig. 3a) freely encircling the member 74 and engaging the cross-bar. The lower end of lever 90 extends through an opening in the bottom of casing 60 and is there fulcrumed on the rounded point of a screw 91, against which it is held by a spring-urged pin 92. The lever 90 is biased in counterclockwise direction by the force of a relatively stiff spring 93 backed by a nut 94 threaded on member 74.

For operating the lever 90 there is mounted on the top of the casing 60 an electric solenoid 95, the plunger 96 of which is connected by a link 97 to an arm 98 pivoted on the casing and having a finger 99 engageable with a screw 100 in the upper portion of lever 90. A leaf spring 101, below the plunger and held in place by a helical spring 102, serves as means for cushioning the fall of the plunger to the position shown (after it has been raised by energization of the solenoid).

Interposed between the pointed extremities of the rods 70 and 85 is a cam 103 formed by a pair of opposed conical pieces secured to a plate 104. The plate 104 is pivoted on an arm 105 which in turn is pivoted on another plate 106, so that the rods 70 and 85 can move longitudinally, carrying the cam 103 with them. Thus, with the parts in the positions shown in Fig. 3, if the solenoid 95 is energized and the lever 90 thereby rocked clockwise out of engagement with the cross-bar 88, the rods 70 and 85 can move in a right-hand

5

direction, under the force of spring 12, to a position wherein the cross-bar 88 has been moved by the rod 85 to the right-hand end of its slot 87 (indicated in Fig. 4).

The plate 106 is secured to a shaft 107 which extends into the interior of the spacing member 23 (Fig. 2) and is there secured to an arm 108 which is connected by a link 109 to a plate 110 secured to the lower diaphragm-plate 29. By this connection, and the arm 105 shown in Fig. 3, movement of the diaphragm 26 effects rocking of the cam 103, so that the effective combined length of rods 70 and 85 is varied. In the outer surface of the shaft 107 is a groove 111 (Fig. 3) which affords fluid communication between the interior of the spacing member 23 (and, hence, the inlet 15) and the compartment 112 adjacent the valve structure 47; this compartment being otherwise sealed.

The operation of the apparatus shown in Figs. 2 and 3 will now be described in connection with the burner system of Fig. 1. It will be observed that in Fig. 1 fuel is being supplied to the burner 12 (as evidenced by the flames 113) and that the damper 114 is in partly-open position due to the elevated condition of the diaphragm 26 and the damper arm 35 connected thereto. In Figs. 2 and 3 the parts are shown in their normal positions, corresponding to a cold condition of the furnace.

The solenoid 41 is connected by wires 115, in series with a control device 116, to terminals 117 which, it is to be assumed, are those of an electric source, preferably of low voltage. The control device 116 may be such as a manual switch, a time-clock, or a safety or limit-control responsive to a condition resulting from the operation of the burner system and acting to open the circuit of solenoid 41 in the event said condition becomes abnormal. As was previously described, deenergization of the solenoid 41 effects seating of the main closure 19.

The other solenoid 95 is connected by wires 118 to the electric source in series with the control device 116 and another control device 119 which may be a thermostat responsive to the temperature of a space heated by steam (passing thereto through pipe 120) from the boiler 11.

However, in a particular application of the present invention, and as indicated in Fig. 1, the control device 119 is arranged to respond to draft in the furnace-stack 121; the device being responsive either to the temperature of the stack or to flow of burnt gases therethrough, and being so arranged that its circuit-controlling elements are open until proper draft has been established.

When, to initiate operation of the system, the solenoid 41 is energized, the pilot-valve closure 40 is raised so that, since (as seen in Fig. 3) the closure 65 of the valve structure 47 is spaced by a short distance from its seat 66 and the pipe 46 therefore in communication with the vent pipe 49, pressure in the diaphragm chamber 27 is relieved and the diaphragm and closure 19 rise; permitting fuel to pass to the burner 12 where it is lighted by a pilot burner or other conventional igniting means (not shown).

However, assuming that the furnace stack is cold, or that there is insufficient draft therethrough, and the contacts of the control device 119 are therefore open so that the other solenoid 95 is unenergized, upon rise of the closure 19 to a position wherein gas is supplied to the burner in an amount sufficient to produce a "low-fire" in the furnace, the resultant rocking of the cam

6

103 in a clockwise direction (as indicated by the arrow and legend "Open" in Fig. 3) effects such movement of the rod 70 as to bring the closure 65 into engagement with its seat 66 (the closure following the movement of the rod under the force of spring 69) whereupon the venting of the diaphragm chamber 27 is interrupted, so that upward movement of the diaphragm and closure 19 is arrested. The low-fire position of the closure 19 is set by adjustment of the stop-nut 89 which (under the conditions indicated in Fig. 3) determines the position of cross-bar 88 and rod 85, and thereby the initial position of rod 70 and closure 65.

When, due to the low-fire, there is proper draft in the stack 120, the contacts of the control device 119 close so that the solenoid 95 is also energized. The resultant clockwise rocking of the lever 90 out of engagement with the cross-bar 88 effects movement of the rods 70 and 85, under the force of spring 72, to a position wherein the cross-bar is at the right-hand end of its slot 87. Since the closure 65 is now widely spaced from its seat, the diaphragm chamber 27 is completely vented and the diaphragm and closure 19 rise to their full extent. By this rise of the diaphragm the cam 103 is rocked to a horizontal position wherein the effective combined length of the rods 70 and 85 is the greatest (the effective combined length of the rods being the least when the cam is in the position shown in Fig. 3). Such lengthening of the rods is, however, now ineffective to cause seating of the closure 65; the approximate relative positions of the parts under the conditions just described being shown in Fig. 5.

When, due to the high-fire condition now established in the furnace, steam is generated in the boiler, its pressure acting on the bellows-head 79 gradually forces the stem 75 inwardly so that it engages the cross-bar 88 and then moves the same, together with the rods 85 and 70 and cam 103, in a left-hand direction. After the closure 65 engages its seat 66 (the closure following the movement of the rod 70 under the force of spring 69), continued movement of the rod 70 unseats the ball closure 71 so that pressure-fluid can pass from the chamber 112 (which, as previously described, is in communication with the inlet 15) through the tubular member 64, and thence through fitting 67, pipe 46, and the now-energized pilot valve 37, to the diaphragm chamber 27; the diaphragm moving downwardly by gravity due to the equalization of the pressure above and below it. However, due to the follow-up connection (comprising cam 103) between the diaphragm and the valve structure 47, the downward movement of the diaphragm (and closure 19) is quickly checked due to the reseating of the ball closure 71 resulting from the rocking of the cam and decrease of the effective combined length of the rods 70 and 85.

If the steam pressure rises despite reduction of supply of fuel to the burner, the operation is repeated and the diaphragm and closure 19 arrested in still lower positions; the supply of fuel being progressively throttled down until (if the steam pressure continues to rise) farther movement of the motor stem 75 is prevented by engagement of the cross-bar 88 with the stop-nut 89; the position of closure 19 then being such that the burner is on low-fire.

With decrease of steam pressure, the resultant right-hand movement of stem 75 effects unseating of the closure 65 and progressive rise of the

diaphragm as its chamber 21 is vented and then reclosed due to the follow-up operation of the closure 65.

The structure shown in Fig. 4 is identical with that of Fig. 3 except for the omission of the pressure motor 76 and its associated parts; the empty end of casing 60 being covered by a plate 122. With the arrangement shown in Fig. 4, the burner can be operated on high-fire or low-fire (while the solenoid 41, controlling pilot valve 37, is energized) as, for example, by controlling the energization of solenoid 95 by means of a thermostat responsive to the temperature of a space heated by the furnace; the solenoid 95 when energized effecting, through lever 90, movement of the controlling parts to their high-fire positions as shown in Fig. 5; these parts being returned, under the superior force of spring 93, to their low-fire positions (generally as shown in Figs. 3 and 4) upon deenergization of solenoid 95.

The specific embodiments of my invention herein shown and described are obviously susceptible of modification without departing from the spirit of the invention, and I intend therefore to be limited only by the scope of the appended claims.

I claim as my invention:

1. In a fluid-pressure operated control system: means defining a pressure chamber and including a wall movable between limiting positions in response to change of pressure in the chamber; a source of pressure fluid; first valve means for controlling passage of said pressure fluid with respect to said chamber to effect movement of said wall in opposite directions; second valve means also controlling said passage of pressure fluid; means forming a follow-up connection between said second valve means and said wall whereby movement of the wall effects movement of the second valve means; means normally so conditioning said second valve means that, through said follow-up connection, the second valve means is effective to arrest the wall in a predetermined position intermediate said limiting positions; and means for rendering said conditioning means ineffective so that the wall can then move throughout its full range under the control of said first valve means.

2. In a fluid-pressure operated control system: means defining a pressure chamber and including a wall movable between limiting positions in response to change of pressure in the chamber; a source of pressure fluid; first valve means for controlling passage of said pressure fluid with respect to said chamber to effect movement of said wall in opposite directions; second valve means also controlling said passage of pressure fluid; means forming a follow-up connection between said second valve means and said wall whereby movement of the wall effects movement of the second valve means; said follow-up connection normally being such that movement of the wall to a predetermined position intermediate said limiting positions effects such operation of the second valve means that the resultant pressure in said chamber arrests the wall in said intermediate position; and means for so altering said follow-up connection that the same is ineffective to operate the second valve means, and the wall can then move throughout its full range under the control of said first valve means.

3. In a fluid-pressure operated control system: means defining a pressure chamber and including a wall movable between limiting positions in response to change of pressure in the chamber; a

source of pressure fluid; first valve means for controlling passage of said pressure fluid with respect to said chamber to effect movement of said wall in opposite directions; second valve means also controlling said passage of pressure fluid and comprising means forming a valve seat and a closure cooperable with said seat; means forming a follow-up connection between said closure and said wall whereby movement of the wall effects movement of the closure; means normally positioning said closure in operative relation to said follow-up connection so that movement of the wall to a predetermined position intermediate said limiting positions effects such movement of the closure relative to its seat that a pressure condition is established in said chamber whereby the wall is arrested in said intermediate position; and means for so altering the position of the closure relative to the follow-up connection that the wall can then move throughout its full range, under the control of said first valve means, without effecting operative movement of the closure relative to its seat.

4. In a fluid-pressure operated control system: means defining a pressure chamber and including a wall movable between limiting positions in response to change of pressure in the chamber; a source of pressure fluid; three-way valve means having a pair of passages whereby in one controlling position of the valve means said pressure fluid is supplied to said chamber through one of said passages to move the wall in one direction, and in the alternate controlling position of the valve means said chamber is vented through the other of said passages to effect movement of the wall in an opposite direction; additional valve means for controlling flow through a given one of said passages; means forming a follow-up connection between said wall and said additional valve means; means normally so conditioning said follow-up connection that, when the wall is in a predetermined position intermediate said limiting positions, flow through said given one of said passages is obstructed by said additional valve means; and means for rendering said conditioning means ineffective so that the wall can then move throughout its full range without effecting obstruction of flow through said given one of the passages.

5. In a fluid-pressure operated control system: means defining a pressure chamber and including a wall movable between limiting positions in response to change of pressure in the chamber; a source of pressure fluid; three-way valve means having a pair of passages whereby in one controlling position of the valve means said pressure fluid is supplied to said chamber through one of said passages to move the wall in one direction, and in the alternate controlling position of the valve means said chamber is vented through the other of said passages to effect movement of the wall in an opposite direction; additional valve means for controlling flow through a given one of said passages and comprising means forming a valve seat and a closure cooperable with said seat; means forming a follow-up connection between said closure and said wall whereby movement of the wall effects movement of the closure; means normally positioning said closure in operative relation to said follow-up connection so that movement of the wall, to a predetermined position intermediate said limiting positions, effects seating of said closure and thereby obstruction of flow through said given one of the passages; and means for so altering the posi-

tion of the closure relative to the follow-up connection that the wall can then move throughout its full range without effecting seating of the closure.

6. In a fluid-pressure operated control system: means defining a pressure chamber and including a wall movable between limiting positions in response to change of pressure in the chamber; a source of pressure fluid; three-way valve means having a pair of passages whereby in one controlling position of the valve means said pressure fluid is supplied to said chamber through one of said passages to move the wall in one direction, and in the alternate controlling position of the valve means said chamber is vented through the other of said passages to effect movement of the wall in an opposite direction; additional valve means for controlling flow through a given one of said passages and comprising means forming a valve seat and a closure cooperable with said seat; means forming a follow-up connection between said closure and said wall, and including a cam whereby movement of the wall effects movement of the closure toward and away from its seat; said connection also including means whereby said closure and said cam can move, as a unit, independently of said wall; means normally maintaining said unit adjacent said seat so that movement of the wall to a predetermined position intermediate said limiting positions effects, through said cam, seating of said closure and thereby obstruction of flow through said given one of the passages; and means for moving said closure-and-cam unit to a position away from said valve seat so that the wall can then move throughout its full range without effecting seating of the closure.

7. In a fluid-pressure operated control system: means defining a pressure chamber and including a wall movable between limiting positions in response to change of pressure in the chamber; a source of pressure fluid; three-way valve means having a pair of passages whereby in one controlling position of the valve means said pressure

fluid is supplied to said chamber through one of said passages to move the wall in one direction, and in the alternate controlling position of the valve means said chamber is vented through the other of said passages to effect movement of the wall in an opposite direction; additional valve means for controlling flow through a given one of said passages and comprising means forming a valve seat and a closure cooperable with said seat; means forming a follow-up connection between said closure and said wall, and including a cam whereby movement of the wall effects movement of the closure toward and away from its seat; said connection also including means whereby said closure and said cam can move, as a unit, independently of said wall; a spring biasing said unit to a position remote from said seat; stop means for maintaining said unit, against the force of said spring, in a position adjacent said seat so that movement of the wall to a predetermined position intermediate said limiting positions effects, through said cam, seating of said closure and thereby obstruction of flow through said given one of the passages; and means for removing said stop means so that said closure-and-cam unit then moves to its biased position away from said seat, and the wall can move throughout its full range without effecting seating of the closure.
